United States Patent Office

Des. 185,717
Patented July 21, 1959

185,717

GOLF CLUB HEAD

Haydon L. Newton, Portland, Oreg.

Application January 24, 1958, Serial No. 49,397

Term of patent 7 years

(Cl. D34—5)

Figure 2 is a front elevation view of the club head; Figure 3 is a top plan view of the club head; and Figure 4 is an end elevation view of the club head.

I claim:

The ornamental design for a golf club head, as shown.
